UNITED STATES PATENT OFFICE.

CHARLES JOHNSON, OF ROCKFORD, ILLINOIS.

AIR PUMP.

Application filed November 8, 1921. Serial No. 513,729.

To all whom it may concern:

Be it known that I, CHARLES JOHNSON, a citizen of the United States, residing at Rockford, in the county of Winnebago and 5 State of Illinois, have invented certain new and useful Improvements in Air Pumps, of which the following is a specification.

This invention pertains in general to pumps, and has more particular reference 10 to air pumps adapted for inflating pneumatic tires and replenishing air pressure tanks, containers, etc.

The primary object of the present invention is to provide a novel air pump adapted 15 to function more efficiently and having a greater capacity delivery for a given size than the commercial pumps now in use.

Another object is to provide as a new article of manufacture, an air pump of high 20 efficiency and constructed in such manner as to be capable of production at a comparatively low cost and which will be practical and durable for the purposes intended.

More particularly, my invention contemplates 25 the provision of an air pump characterized by a cylinder and piston, an auxiliary air supply compartment, preferably in the form of a barrel alongside of the cylinder, and valve-controlled passages between the cylinder and said compartment and at the induction end of said cylinder, so constructed and arranged that by means of the single piston or plunger an air supply under pressure will be maintained in said 30 compartment and delivered to the cylinder, filling the latter to capacity and enabling capacity delivery under the pressure stroke of the piston. In other words, by means of a single cylinder piston, the return stroke 35 40 is utilized to build up an air supply for delivery to the cylinder which will be filled to capacity prior to each pressure stroke.

Other objects and attendant advantages 45 will be appreciated by those familiar with this art as the invention becomes better understood by reference to the following description when considered in connection with the accompanying drawings, in which—

Figure 1 is a longitudinal sectional view 50 through an air pump embodying my invention; and

Figs. 2 and 3 are cross-sectional views taken respectively on the lines 2—2 and 3—3 of Fig. 1.

55 In illustrating the principles of this invention, I have taken as an example, a hand

pump of the type adapted to be held in vertical position by means of a foot bracket. It should be understood, however, that the invention is capable of embodiment in other 60 forms with relation to the manner and position in which the cylinder is supported and to the means for reciprocating the piston.

In the present example, I have provided a cylinder 4 in the form of an open-end tube 65 closed at one end by a base bracket 5, and at its opposite end by a top bracket 6. A suitable piston 7, reciprocable in the cylinder has a stem 8 passing through the top bracket 6 and equipped at its upper end with a 70 handle 9. A suitable packing nut 11 on the top bracket seals the passage of the stem through said bracket. In this type of hand pump any suitable bracket may be employed for holding the pump in upright position, 75 and in the present example I have shown a bracket 12 in the form of a rod pivotally attached at 13 to the base bracket and adapted to be swung on its pivot to and from operative and inoperative positions, as 80 shown. The top bracket has an inlet or induction port 14 normally closed by a spring-pressed valve 15, and the base bracket has an eduction port in which is secured a hose coupling 16, the air delivery for service 85 being through this eduction port as is well understood.

An auxiliary air compartment is now provided preferably in the form of a barrel 17 alongside of the cylinder and secured at its 90 ends in the top and base brackets. The induction end of the cylinder and the adjacent end of the barrel are connected by a passage 18 formed in the top bracket, in which passage is interposed a suitable check valve, 95 permitting passage of air from the cylinder to the barrel but checking it in the reverse direction. This check valve at present is shown in the form of a ball 19 held on its seat by a spring 21, the pressure of which 100 may be adjusted by a screw 22. The eduction end of the cylinder is also connected with the adjacent end of the barrel by means of a passage 23 in which is interposed a check valve 24, but this valve is arranged 105 to prevent passage of air from the cylinder to the barrel. A suitable spring 25 and adjusting screw 26 are employed for holding the ball valve in operative position.

In the present form a pair of tie rods 27 110 are employed between the top and base brackets for clamping them onto the inter-

posed cylinder and barrel and for holding the parts in rigid relation.

The operation is as follows: When the piston is moved downwardly on the pressure stroke, air will be drawn into the upper end of the cylinder through the port 14. On the return stroke, the induction port will be closed by the valve 15 and the air in the cylinder above the piston will be forced through the passage 18 into the barrel 17. The air in the barrel 17 will thus be held under compression as determined by the check valve 24, and when the air pressure exceeds that of the pressure of the spring 25, the ball valve will be lifted, and air will escape into the cylinder below the piston. Upon the next downward stroke the air in the cylinder below the piston will be forced out through the eduction port and fresh air will be drawn into the upper end of the cylinder. This fresh air will then be forced into the barrel 17 on the next succeeding up stroke, and upon this up stroke sufficient air will be forced through the passage 23 to completely fill the cylinder below the piston. It follows, therefore, that upon each return stroke of the piston the delivery end of the cylinder will be filled to capacity, and that each pressure stroke will deliver through the eduction port this volume of air which is the full capacity of the cylinder. It will be manifest that a pump of this character will be highly efficient by reason of the fact that the return stroke is employed to deliver a positive supply of air under pressure to the cylinder, and which supply fills the cylinder to capacity.

It is believed that the foregoing conveys a clear understanding of the objects prefaced above, and while I have illustrated but a single working embodiment, it should be understood that considerable change might be made in the construction and arrangement

without departing from the spirit and scope of the invention as expressed in the appended claims: in which—

I claim:

1. A pump of the character described comprising a base and a top bracket, a pair of tubular bodies interposed between said brackets, one providing a cylinder and the other an air compartment, a piston in the cylinder, means for reciprocating the piston, an induction valve for admitting air to the upper end of the cylinder, a passage in the top bracket connecting the cylinder and air chamber and having a check valve permitting flow of air only from the cylinder to the chamber, an eduction valve in the bottom end of the cylinder, and a passage in the bottom bracket connecting the cylinder and air chamber and having a check valve for permitting flow of air only from said chamber to the cylinder.

2. A pump as set forth in claim 1, including tie rods for clamping the top and bottom brackets on the interposed tubular bodies.

3. An air pump, as set forth in claim 1 including tie rods for clamping the top and bottom brackets on the interposed tubular bodies, said tubular bodies being laterally spaced apart and the tie rods being disposed on opposite sides of a plane intersecting the longitudinal axes of said bodies.

4. An air pump as set forth in claim 1 including tie rods for clamping the top and bottom brackets on the interposed tubular bodies, said tubular bodies being laterally spaced apart and the tie rods being disposed on opposite sides of a plane intersecting the longitudinal axes of said bodies, and in which the check valves are interposed between the tubular bodies and the tie rods.

CHARLES JOHNSON.
